United States Patent Office

Des. 206,831

Patented Jan. 31, 1967

206,831

BOTTLE

Clare E. Hodgman, Mamaroneck, N.Y., assignor to The Coca-Cola Company, Atlanta, Ga., a corporation of Delaware

Filed Jan. 10, 1966, Ser. No. 617

Term of patent 14 years

(Cl. D58—8)

Fig. 1.

Fig. 2.

Fig. 3.

Fig. 4.

I claim:

The ornamental design for a bottle, as shown.
